United States Patent

Des. 239,862
Patented May 11, 1976

239,862

INDUSTRIAL ROBOT OR THE LIKE

John J. Wallace, Richland, Mich., assignor to
Prab Conveyors, Inc.

Filed June 4, 1973, Ser. No. 366,724

Term of patent 14 years

Int. Cl. D15—99

U.S. Cl. D55—1 R

figure 1

figure 2

figure 3

figure 4

FIG. 1 is a rear perspective view of an industrial robot showing my new design with the grip partially extended;

FIG. 2 is a side elevational view thereof showing the grip partially extended;

FIG. 3 is an elevational view as seen from the opposite side of FIG. 2 with the grip retracted; and

FIG. 4 is a front elevational view thereof.

I claim:

The ornamental design for an industrial robot or the like, substantially as shown.
